UNITED STATES PATENT OFFICE.

WILLIAM A. COOK, OF MARION, INDIANA, ASSIGNOR TO JOHN A. SHAFFER, OF INDIANAPOLIS, INDIANA, AND ORA C. KING, OF MARION, INDIANA.

RAILWAY GATE.

Application filed May 26, 1928. Serial No. 280,679.

My invention relates to improvements in railway crossing gates and particularly to that type of crossing gate which is automatically closed upon the approach of a train to 5 the crossing and automatically opened when the train has passed the crossing.

One of the objects of my invention is to provide a gate which when in closed position is movable to permit passage thereby of a vehicle which might happen to be caught between the gates when the same are lowered.

Another object of my invention is to provide a gate, the operating mechanism of which is such that in event of the failure of control 15 thereof the gate will drop to closed position.

For the purpose of disclosing my invention I have illustrated one embodiment thereof in the accompanying drawings in which—

Fig. 1 is an elevation of a gate showing the 20 same in raised or open position;

Fig. 2 is a longitudinal sectional view of the gate operating mechanism showing the gate swung to permit the passage thereby;

Fig. 3 is a transverse section of the operating mechanism;

Fig. 4 is an enlarged longitudinal section, and

Fig. 5 is a diagrammatic view of the circuit arrangement for controlling the operation of the gate.

In the embodiment of the invention illustrated, I provide, for each gate, a support or standard comprising a cylindrical base 1 which may be bolted or otherwise secured to a foundation 2 and this base is covered by a cap 3 on which the gate proper 4 is pivotally mounted on a shaft 5 extending horizontally through the cap. The gate is suitably counter-weighted at its end by weights 6 to 40 permit the same to rock readily on its pivot.

The rotatable cap 3 is rotatably supported on a vertical shaft 7 which rotates in bearings 8 and 9 formed in the ends of supporting arms 10 and 11 integrally formed with the 45 walls of the casing 1. This rotating shaft supports the operating mechanism for controlling the raising and lowering of the gate arm 4. To this end I mount on the shaft 7 a platform 12 which supports a vertically extending fluid cylinder 13 which is provided with a reciprocating piston 14, the piston rod 15 of which is connected with one end of a crank arm 16 keyed on the shaft 5.

The bottom of this cylinder communicates 55 by means of a supply pipe 17 with the intake

18 of an oil pump 19, the pump being mounted on the platform 12 and the cylinder at a point above the piston communicates by means of a pipe 20 with the intake 21 of the cylinder beneath the piston 14. Arranged in 60 this piping is a valve 22 controlled by a solenoid 23, the arrangement being such that the valve is normally closed and also arranged in the pipe 20 is a valve 24 which may be adjusted to control the rate of flow of fluid through this pipe. The pump 19 is operated by a suitable electric motor 25 also mounted on the platform 12 and communicates with the top of the cylinder 13 by means of the pipe 26.

Formed on the inner face of the cylinder 1 is a pair of cam tracks 27 and 28 which are inclined upwardly and on which a roller 12' on the platform 12 is adapted to operate.

The circuit through the electro-magnet 23 75 may be controlled by any suitable means, as by a switch or other mechanism operated by the passage of a car or train into the block of the track. Under normal circumstances the valve is maintained closed by the electro-magnet which is in a normally energized circuit. Assuming for the purpose of understanding the operation, that the gate is in its raised or open position with the valve 22 closed, the liquid in the cylinder 13 beneath the piston 80 14 will maintain the gate against its bias towards closed position. As soon as a train enters the block the electro-magnet 23 is de-energized thereby opening the oil circuit through the pipe 20 and the piston under the 90 weight of the gate will be permitted to drop, the oil passing out of the bottom of the cylinder 13 through the valve 22 and into the top of the cylinder. After the train has passed through the block the circuit through the elec- 95 tric motor 25 will be closed by any suitable instrumentality operated from the track and the motor will then operate the pump ex- hausting the oil from above the piston 14 by way of the pipe 26 and delivering the oil 100 through the pipe 27 beneath the piston 14, thereby elevating the piston and with it the gate, it being understood that at the time of the passage of the train out of the block the electro-magnet 23 will be operated to close 105 the valve 22. The electric motor will con- tinue to operate to pump the oil into the cylinder beneath the piston 14 until the gate has reached its elevated position, at which time 110

raised to a sufficient point to operate a suitable pressure switch 29 to open the motor circuit.

The speed at which the gate may be elevated may be controlled by a suitable valve 30 which may be adjusted to control the flow of oil into the cylinder.

If desired, instead of the cylinder 12 above the piston 14 acting as a reservoir for the oil 10 when the gate is moved to its lower position, a pipe 31 may be extended into a reservoir 32 located in the base 2.

A suitable key controlled switch block 33 is provided by which the circuit of the motor 15 25 may be manually controlled when desired.

It will be noted that all of the parts are so mounted on the shaft 7 that the entire operating mechanism for the gate is supported from 20 and rotatable with this shaft. The gates being mounted in the cap 3 which is rotatable with the shaft 7, provide means whereby the gates may be rotated under abnormal circumstances, as for instance a vehicle caught on the track when all of the gates are lowered.

25 Under these circumstances, by pushing on the gates they may be rotated in a horizontal position to permit the passage therethrough of the vehicle. When a gate is rotated in its horizontal position the roller 12' will ride up one of the cam tracks 27 or 28, depending upon the direction in which the gate is rotated, and of course all of the parts carried on the platform will ride up at the same time. Due to the inclination of the cam track, as 30 soon as the gate is released after having been rotated the weight of the parts will cause the roller to ride down the cam track, rotating the gate back to its normal position.

In the diagrammatic view illustrated I provide 40 a relay 34 which is normally biased toward open position and maintained in closed position by the electro-magnet 35. This relay controls the circuit through the solenoid 23 of the solenoid valve 22 and also through 45 the winding of the electric motor 25. The key switch 33 being in series with the motor 25 and the solenoid 23 and the pressure control switch 29 being arranged in series with the motor 25.

50 In operation current from a suitable source of supply passes through the conductor 37, the switch 34, the solenoid winding 35, a relay switch 38 and thence by a conductor 39 to ground, thus establishing a circuit through 55 the solenoid winding 35 and maintaining the switch 34 closed so that the winding 23 is energized and the electric motor is in an operating circuit. In event a car approaches from the left a circuit is established from the trolley by the way of the conductor 40 through the solenoid winding 41 of the switch 38 and thence by conductors 42 and 39 to ground. This momentarily energizes the solenoid winding 41 opening the relay switch 38 and

thus opening the circuit through the winding 35 thereby permitting the switch 34 to open.

As soon as the circuit through the conductor 40 is opened by the passage of the car the switch 38 immediately closes again but, due to the fact that the circuit through the solenoid 35 is still open the circuit through the solenoid 23 controlling the solenoid valve 22 remains open. As the car passes out of the block it closes a circuit from the trolley wire by the way of conductors 43, through the solenoid winding 35, through the switch 38 and by conductor 39 back to ground thus energizing the solenoid 35 and closing the switch 34, thereby re-establishing the solenoid operated switch 23 and motor circuit so that the parts 80 are thrown in operative position again. It is obvious that similar connections for the opposite track may be provided so that cars traveling in the opposite direction will operate the parts in the manner above described. 85

I claim:

1. The combination with a standard, of a vertical shaft mounted therein, a head rotatably carried by said shaft and rotatable in a horizontal plane, a railway gate swingably mounted on said head and swingable in a vertical plane, an arcuate inclined track carried by said standard and an arm on said shaft engaging said track when the head is rotated in a horizontal plane to raise said head where- 90 by when the rotating pressure is released from said head the head will be rotated to its normal position under the influence of gravity. 95

2. The combination with a hollow stand- 100 ard, of a head rotatably mounted on said standard, a vertically extending shaft se- cured to said head, a gate swingable in a vertical plane on said head, means for swinging said gate mounted on said shaft and means carried by said shaft and co-operating with 105 means on said standard for returning said head to normal position when rotated in either direction in a horizontal plane.

3. The combination with a hollow stand- 110 ard, of a head rotatably associated therewith, a gate swingably mounted to swing in a vertical plane carried by said head, a shaft rotatable with said head, a platform carried by said shaft, a cylinder mounted on said platform, a piston operated in said cylinder and connected with said gate, and a pump mounted on said platform for pumping an operating fluid to and from said cylinder for operating said piston and co-operating means on said shaft and standard for returning said head 115 to normal position when the same is rotated in a horizontal plane in either direction. 120

In witness whereof, I, WILLIAM A. COOK, have hereunto set my hand at Indianapolis, Indiana, this 12th day of May, A. D. one 125 thousand nine hundred and twenty eight.

WILLIAM A. COOK.
